UNITED STATES PATENT OFFICE.

HENRY ALLEN DALLEY, OF PHILADELPHIA, PENNSYLVANIA, ASSIGNOR TO THE UNIT CONSTRUCTION COMPANY, OF PHILADELPHIA, PENNSYLVANIA, A CORPORATION OF PENNSYLVANIA.

DESIGN FOR A SALES COUNTER OR CABINET.

51,299.

Specification for Design.

Patented Sept. 25, 1917.

Application filed November 20, 1916. Serial No. 132,480. Term of patent 7 years.

To all whom it may concern:

Be it known that I, HENRY ALLEN DALLEY, a citizen of the United States, residing at Philadelphia, county of Philadelphia, and State of Pennsylvania, have invented a new, original, and ornamental Design for a Sales Counter or Cabinet, of which the following is a specification, reference being had to the accompanying drawing, forming a part thereof, wherein—

The figure is a perspective view of my new design for a sales counter or cabinet.

I claim:

The ornamental design for a sales counter or cabinet as shown.

HENRY ALLEN DALLEY.

Witnesses:

MARY E. LOGAN,
L. J. RICHARDSON.
